UNITED STATES PATENT OFFICE.

WILLIAM S. GRAHAM, OF CANTON, ILLINOIS, ASSIGNOR TO THE PARLIN & ORENDORFF COMPANY, OF SAME PLACE.

CULTIVATOR.

SPECIFICATION forming part of Letters Patent No. 660,103, dated October 23, 1900.

Application filed July 17, 1900. Serial No. 23,926. (No model.)

To all whom it may concern:

Be it known that I, WILLIAM S. GRAHAM, of the city of Canton, county of Fulton, and State of Illinois, have invented certain new and useful Improvements in Cultivators, of which the following is a specification.

This invention relates to riding-cultivators. It pertains in part to means for controlling the depth of cultivators and in part to means for providing either horizontal side swing or pendulous side swing in the cultivator-beams and the shovels thereon. It is exemplified in the structure hereinafter described and it is defined in the appended claims.

15 In the drawings forming part of this specification, Figure 1 is a diagram in side elevation, showing the general outline of some of the essential features of a riding-cultivator in broken lines and illustrating in solid lines the parts that embody my invention. Fig. 2 is a central vertical section through the compound coupling for the front end of the cultivator-beam. Fig. 3 is a front elevation of the coupling for the front end of the cultivator-beam, the part of the beam that engages with the coupling being omitted. Fig. 4 is a plan of the front coupling. Fig. 5 is a detail of the vertical extension of a beam, showing an adjusting-collar fastened thereon. Fig. 6 is 20 a rear elevation of the coupling that connects the pendulous supporting-rod with the beam, showing the coupling connected rigidly to the beam and representing in broken lines the effect of such stiff connection when the rod 25 swings sidewise. Fig. 7 is a front elevation of the coupling shown in Fig. 6, the connection with the beam being pivotal in this instance and the result of the pivotal connection being shown in broken lines. Fig. 8 is 30 a detail, partly in side elevation and partly in section, of the device used to control the depth of cultivation. Fig. 9 is a plan of the depth-controlling plate.

A supporting-wheel for a cultivator is shown 35 at 1 and a crank-axle therefor at 2. A side bar of the cultivator-frame is shown at 3, a beam at 4, a vertical shaft extension of the beam at 5, a beam-supporting rock-arm at 6, a pendulous connecting-rod at 29, and a seat 40 at 7. A saddle 40 is fixed onto the upper surface of the upper horizontal extension or

bridge of the crank-axle. It has a pair of vertical lugs 39, and the rock-arm 6 for the pendulous beam-supporting rod 29 is pivoted at 41 on a pin carried by the lugs. A lever 8 55 is also pivoted on pin 41, and such lever extends both to the front and to the rear of the pivot. A rod 10 is connected with a yoke 9 on the rock-arm 6 and extended through an opening in the front extension of lever 8. A 60 nut 42 is on the forward end of rod 10, and a compression-spring 11 is placed on the rod between the nut and the lever. The rearward end of the lever 8 is preferably forked to hold the pendulous rod 29 when the beam 65 is raised by swinging the rock-arm forward, and it has a stop-bearing 8^a on its under surface. A slide 35 is mounted on saddle 40, between the lugs thereof, and it has a rearward-extended bearing-surface 36, against which 70 the stop-bearing 8^a of lever 8 strikes when the beam is lowered sufficiently to use the resistance of the cushion-spring 11. The spring offers somewhat-stubborn resistance to further depression or lowering of the 75 beam after the lever strikes the stop-block, and it raises the beam promptly after spring-compressing foot-pressure is released. The lever 8 swings on pivot 41 with rock-arm 6 until the stop-block arrests such action, 80 and the point in the descent of the beam at which the lever strikes the stop-block and begins to compress spring 11 to a great extent determines the depth of cultivation. The time in the swing of the rock-arm at 85 which the swing of the lever is arrested depends on the location of stop-bearing 36, and this may be varied without altering the height to which the beam is raised by the forward swing of the rock-arm by shifting slide 35 90 forward and backward. The slide-plate 35 is slotted at 37, as shown in Fig. 9, and a bolt 39, extending through the saddle 40 and through the slot, provides means for adjusting the slide-plate. The contacting surfaces of the saddle and the slide-plate are correspondingly corrugated.

At the front part of the frame is a transverse rod or shaft 12, on which is mounted a sleeve 13. A collar 14 is fastened onto the 100 sleeve. It extends above the shaft 12, and it is bored from front to back through such up-

ward extension. Lugs 16 extend laterally from the upward extension 15 of the collar. A sleeve 17 forms a vertical pivot for the forward extension 5 of the cultivator-beam. It has a stud 19, which extends through the front-to-back bore of the collar, and it has lugs 18, which coincide with lugs 16 of the collar when the sleeve is in a vertical position. The front wall of the sleeve 17 is recessed at 21, as shown in Fig. 3. A bolt 20 extends through stud 19 with its head flush with the inner surface of the recess. A collar 23 is set into the recess with its bore in line with the bore of the sleeve, and when the vertical shaft 5 of the beam is inserted through the sleeve and the collar therein to a proper extent a set-screw 25 in the collar is made to engage the extension of the beam and hold it against up-and-down motion in the sleeve. The collar 20 cannot move up and down in the sleeve, and the extension 5 cannot move up and down in the collar when the set-screw 25 is set; but both the extension and the collar may swing sidewise to a considerable degree in their bearings in the sleeve. The stud 19 forms a horizontal pivot on which the beam may rock from side to side, and the bolt 20, with its securing-nut, holds the stud in the collar. When it is desired to swing the beam from side to side in a horizontal plane, the lugs 18 are secured to lugs 16 by bolts 22, and the pivot 19 is thereby locked or rendered ineffective. The sleeve 17 will then maintain a vertical position, and the extension 5 will rock in the sleeve as the beam swings horizontally. When it is desired to rock the beam with a pendulous motion, the lugs 16 are disconnected from the lugs 18 and the beam is rocked with the horizontal stud 19 for a pivot, while the shovels rise as they travel away from the center of the swing and descend as they swing under a line drawn through the horizontal pivot.

To facilitate the change in the movement of the beam, as hereinbefore described, the pendulous beam-sustaining rod 29 is connected with the beam by a pivotal joint that may be locked to compel the beam to rock on pivot 19. This coupling is shown in Figs. 1, 5, 6, and 7, and its construction is as follows: A sleeve 26 is held crosswise of the beam 4 between two members thereof, and it has lugs 27, equidistant from its longitudinal center and in a vertical plane tangential with its front face. A hanger 30 is fastened onto the lower end of rod 29, and its lower end is forked to straddle the sleeve 26. A pair of arms 32 overlap the lugs 27, and both the lugs and the arms have bolt-holes that coincide when the rod 29 is at right angles with the sleeve 26. When the front coupling is locked against pendulous swing on the horizontal pivot, the lugs 27 are disconnected from arms 32, and the rod rocks on trunnions 34 and 34^a while the beam swings horizontally; but when the beam is permitted to

swing on pivot 19 the arms 32 are fastened to the lugs by bolts 28, and the beam and its shovels are forced to partake of the pendulous motion of rod 29. The hanger 30 is made in two parts, which are clamped onto the rod 29 by a bolt 33, and one trunnion of sleeve 26 is engaged by an extension 31 on one part of the hanger, while the other trunnion is engaged by an extension 31^a on the other part of the hanger.

In describing the invention only one beam and adjuncts thereof have been described; but it will be understood that a plurality of beams are used in a modern cultivator and that one operates like another.

I claim—

1. In a convertible horizontal pivot and vertical pivot for the front end of a cultivator-beam, the combination of a cross-shaft on the front end of the cultivator-frame, a collar on the cross-shaft having an upward extension bored from front to back, a vertical sleeve in which a vertical extension of the beam journals, a stud on the sleeve journaled in the front-to-back bore of the collar and means for holding the stud from turning in its bearing, substantially as described.

2. In a convertible horizontal pivot and vertical pivot for the front end of a cultivator-beam, the combination of a cross-shaft on the front end of the cultivator-frame, a collar on the cross-shaft having an upward extension bored from front to back, a sleeve in front of the shaft, forming a bearing for a vertical extension of the beam, a stud on the sleeve journaled in the front-to-back bore of the collar, lugs on the collar, lugs on the sleeve coinciding with the lugs on the collar when the sleeve is vertical and means for fastening the lugs of the sleeve to lugs of the collar, substantially as described.

3. In a convertible horizontal pivot and vertical pivot for the front end of a cultivator-beam, the combination of a cross-shaft on the front end of the cultivator-frame, a collar on the cross-shaft having an upward extension bored from front to back, a sleeve in front of the shaft cut away in one of its sides and having a stud journaled in the front-to-back bore of the collar, a clamp-collar in the cut-away part of the sleeve holding a vertical extension of the cultivator-beam, and means preventing the stud of the sleeve from turning in the collar on the cross-shaft, substantially as described.

4. In a cultivator, the combination of a beam, a horizontal strut-sleeve fastened between members of the beam, a pendulous rod for supporting the beam, a hanger on the lower end of the rod straddling the strut-sleeve and connecting pivotally therewith between the ends thereof, lugs on the strut-sleeve off the center thereof, arms on the hanger corresponding with the lugs on the sleeve, and means for fastening the arms to the lugs, substantially as described.

5. In a cultivator, the combination with a beam, a beam-sustaining rock-arm, a lever swingable with the rock-arm and connecting with the arm through a cushion-spring, of a
5 *slidable stop-plate to limit the swing of the lever and control the action of the spring, substantially as described.*

In testimony whereof I sign my name in the presence of two subscribing witnesses.

WM. S. GRAHAM.
